UNITED STATES PATENT OFFICE.

ROSARIO FEDERICO AND LEANDRO SEGALIN, OF TURIN, ITALY.

APPARATUS FOR TRANSMITTING SYNCHRONOUS MOVEMENTS BY ROTATING MAGNETIC FIELDS.

1,182,157.

Specification of Letters Patent.

Patented May 9, 1916.

Application filed May 26, 1913. Serial No. 769,945.

To all whom it may concern:

Be it known that we, ROSARIO FEDERICO and LEANDRO SEGALIN, subjects of the King of Italy, residing at Turin, Italy, have invented certain new and useful Improvements in Apparatus for Transmitting Synchronous Movements by Rotating Magnetic Fields, of which the following is a specification.

10 The present invention relates to an installation for controlling electric clocks by means of a central regulator, by utilizing the magnetic rotating field.

15 The object of this invention consists in arrangements which permit of obtaining considerable saving in current and simplification in mechanisms.

20 The annexed drawing shows a construction of the invention in Figure 4, Figs. 1-3 illustrating the known art. Fig. 1 shows a diagram of a transmitter; Fig. 2 shows a modification; Fig. 3 shows schematically a complete installation, and Fig. 4 shows a form of transmitter. Figs. 5 and 6 show 25 arrangements of the interrupted resistance ring; Fig. 7 shows a complete arrangement for the control of electric clocks; Fig. 8 shows another form of said arrangement.

Fig. 1 shows the scheme of the known arrangements in which a circular shaped resistance r is connected in two diametrically opposite points A and B to a source of current P, and two diametrically opposite movable contacts x, y slide in contact 35 with same, being arranged at the ends of an insulating rod b pivoted in o and connected with the external circuit R.

In Fig. 2 the resistance is divided into n sections $r_1, r_2, \dots, r_n$ connected with 40 a corresponding number of sections of an ordinary collector c on which the brushes x, y , press, the latter being connected with rings in communication with the external circuit. When a threephase 45 current is desired, three brushes at 120° are adopted, and the source of current may be constituted by cells or mechanical generators of continuous or alternating current.

In order to generate a polyphase current, 50 either the collector c may be fixed and the brushes to be caused to turn, or the brushes are fixed and the collector is caused to turn, the contacts being effected at A and B by means of two rings insulated from the

axis and two springs leaning on the same 55 rings.

An arrangement is shown in Fig. 3 in which the collector is fixed and two diametral brushes S_1, S_2 turn upon it, and the rheophores feeding the current from the 60 source P are connected with these brushes while the three-phase current is obtained through three fixed leads at three points C, D, E, equally spaced in the resistance r .

With these arrangements there is however 65 the disadvantage that the consumption of current is fairly high, so that it is impossible to apply the systems to the control of electric clocks. In order to eliminate this disadvantage and reduce the consumption of 70 current to a minimum, according to the invention the arrangement shown in Fig. 4 is adopted in which two batteries of cells or accumulators $P_1, P_2, \dots, P'_1, P'_2$, each having their own elements connected in series, are 75 in opposition or differential connection with regard to one another, and each element is connected to a section of the collector c . The brushes S_1, S_2, S_3 which will be connected, either directly or by gearing, with the 80 transmitting axis, for instance with the axis of one hand of the central regulating clock, collect, because of the successive insertion of the elements P and P' , a polyphase current, which produces a rotating magnetic 85 field in the stator T of the receiver. When however, continuous current is to be used, it is possible to avoid the useless consumption of current in resistances by means of a resistance ring, by adopting the arrangement 90 shown in Fig. 5, in which an elementary resistance ring $r_1, r_2, \dots$ interrupted at M and N is inserted in the circuit of the source of current P. The said ring is thus divided into four sections AM, MB, BN and NA 95 equal to each other, each of which sections is subdivided into many equal or unequal sections, calculated in proportion with the resistance of the external circuit in such a way that the intensity of current in each of the portions passes from the positive maximum to zero, from zero to the negative maximum, from the negative maximum to zero and from zero to the positive maximum again with equal intervals, during a 100 complete revolution of the brushes S_1 .

As in practice it is very advantageous that the polyphase current to be collected from

three equally spaced points of the circular resistance the arrangement shown in Fig. 6 may be adopted, in which the resistance ring is interrupted at three points M, N, Q, so as 5 to form three independent groups. In this case the brushes are kept fixed and the collector is caused to turn with its resistances, or vice versa.

In any case a polyphase current is collected having an approximate sinusoidal shape without requiring the current of the feeding circuit to traverse all the resistances 10 ——. Whatever is the type adopted, the receiver is merely constituted by a stator 15 under the influence of which a small iron bar or a magnet directly connected or not with the pointer of the receiver is arranged.

In the above mentioned case of the so 20 called synchronous clocks, it will then be possible to connect the brushes S₁ S₂ S₃ with the minute hand of the central clock, either directly or by means of a gearing, in order to secure a greater uniformity of movement and to connect the small bar U turning in 25 the receiver stator T, in an analogous way, with the minute hand of another receiving clock, so that the rotation of this hand may follow the movement which takes place in the regulating clock.

30 The mechanism of the receiving clocks may be simplified by arranging in them two stators T₁, T₂, having rotating magnetic fields of different period, for instance one with a period of one hour and another with 35 a period of 12 hours, and by mounting the minute hand on the axis U₁ of the rotor belonging to the stator T₁ and the hour hand on the axis V₂ of the rotor belonging to the stator T₂, so that all gearing trans-

mission is dispensed with (Fig. 7). The 40 same object, however, may be attained with a single current having for instance a period of one hour by forming the second stator T₂ (the one which must move the hour hand) of a winding divided 45 into various sections, so that, even sending a current having a period of one hour, the magnetic field may turn with a period of 12 hours, that is to say by applying the same 50 method employed to reduce the speed of rotating magnetic field motors (Fig. 8). In any case a single transmitter can control several receivers, either connected in series or in derivation.

What we claim as our invention and desire 55 to secure by United States Letters Patent is:—

In an apparatus for transmitting synchronous movements by utilizing a rotating magnetic field, a transmitter having a section 60 current distributer, a current generating element connected with each section, said elements forming two batteries in series connected in opposition with each other, a transmitter axis connected mechanically with the 65 rotary member of the current distributer, said member having brushes contacting with the segments thereof and adapted to be connected electrically with the stator of the receiver.

In testimony whereof we have signed our names to this specification in the presence of two subscribing witnesses.

ROSARIO FEDERICO.
LEANDRO SEGALIN.
